UNITED STATES PATENT OFFICE.

GOTTLIEB W. VOLZ, OF WASHTUCNA, WASHINGTON.

GAS-ENGINE ATTACHMENT.

1,202,926.

Specification of Letters Patent. Patented Oct. 31, 1916.

Application filed January 31, 1914. Serial No. 815,781.

To all whom it may concern:

Be it known that I, GOTTLIEB W. VOLZ, a citizen of the United States, residing at Washtucna, in the county of Adams and State of Washington, have invented new and useful Improvements in Gas-Engine Attachments, of which the following is a specification.

This invention relates to attachments for internal combustion engines, the object of the invention being to provide a simple, economical and reliable carbon remover and preventive, the device being continuously carried by and forming a part of the equipment of the engine and serving to supply moisture to the combustion chambers of the cylinders of the engine in accordance with the requirements, the amount of moisture supply being adjustable and readily controllable.

With the above and other objects in view, the invention consists in the novel construction, combination and arrangement of parts, as will hereinafter be more fully described, illustrated and claimed.

In the accompanying drawings:—Figure 1 is a side elevation partly in section of an engine and radiator as now commonly related to each other in automobile practice, showing also a portion of the frame of an automobile. Fig. 2 is a rear elevation of the radiator, showing the invention applied thereto and partly in section. Fig. 3 is a detail sectional view of the controlling and regulating valves and short circuiting device for the ignition current. Fig. 4 is a detail elevation of the dash control.

Referring to the drawings A generally designates an internal combustion engine, B the ordinary radiator, C the dash and D the frame or chassis of an automobile.

In carrying out the present invention I employ a suction pipe designated generally at E, said suction pipe embodying a section 1 which extends from the intake manifold 2 to the controlling valve-casing, and another section 4 which extends from said valve casing to the water overflow or vent pipe 5 of the radiator, the pipe section 4 being connected to the pipe 5 by means of a T coupling 6 while the pipe 5 extends below said coupling 6 and is provided at its lower extremity with a relief valve 7 to allow for the escape of excess pressure.

An air inlet pipe 8 is supported by and connected with the radiator B and has one

end thereof arranged above the water level and provided with a check valve 9 which admits air to the pipe 8 but prevents the return thereof. The other end of the pipe 8 extends into the radiator and is preferably turned upwardly as at 10 so that the air passing through the pipe 8 will be delivered below the major body of water contained in the radiator, and will percolate upwardly through said body of water into the upper air space 11 of the radiator in which a partial vacuum is constantly maintained by the action of the usual water circulating pump (not shown).

The valve casing 3 is fastened to the front side of the dash C in any convenient manner and is provided with a regulating needle valve 12 having a suitable handle or thumb piece 13 at the other side of the dash which is within convenient reach of the operator. In the same casing is mounted a valve 14 normally held against its seat by means of a spring 13' and adapted to be unseated by means of a push button or plunger 15 within reach of the operator in his seat. The stem 14' of the valve 14 is provided with a cam like projection 15' which, as the push button 15 is thrust inwardly, coöperates with the stem 16' of a short circuiting device 16, the latter being adapted to come into electrical contact with a short circuiting contact piece 17 thereby temporarily cutting out the ignition circuit. The operator opens the valve 14 and cuts out the ignition circuit by operating the push button 15 as above indicated, while the engine is running as in the case of the vehicle descending a grade which causes the pistons to operate in the usual manner, or by racing the engine prior to operating the push button 15. It is to be understood, of course, that cutting off the ignition circuit does not immediately result in the stopping of the engine. While the engine is still turning over and before it stops, the moisture is drawn into the combustion chambers by the suction of the pistons in their respective cylinders.

From the foregoing description it will now be understood that when the valve controlling suction pipe E is opened, the suction in the intake manifold 2 will cause a suction through said pipe E which tends to exhaust the air in the upper air space 11 of the radiator. Thereupon air is drawn past the check valve 9 through a pipe 8 into the bottom of the radiator, the air bubbling up

through the water in the radiator and thus moisture-laden. Such air is conducted through the vent pipe 5 and thence through the suction pipe E into the intake manifold 5 from whence it passes into the several combustion chambers of the cylinders. In this way moisture as it is atomized and carried in the form of a fine spray or vapor into the combustion chambers, is flashed into steam 10 and the oxygen therein combining with the compressed ignited gases, brings any carbon deposits into an incandescent condition whereby the carbon is completely consumed and is carried off through the exhaust valves 15 and manifold.

The invention is particularly desirable in that it enables lower grade fuels to be employed. In case the pressure in the suction pipe should increase to a greater extent than 20 necessary, such excess pressure is carried off by the relief valve referred to.

In many instances, and especially where the interior of the engine is carbonized, the water frequently boils in the radiator, due 25 to the presence of an incandescent coating on the walls of the combustion chamber and head of the piston, creating a considerable steam pressure. In such case, instead of the steam being forced in too large a quantity 30 into the intake manifold, the pressure of the

steam opens the relief valve 7 thus preventing any excess of moisture from being carried into the engine.

What I claim is:—

1. The combination with an internal combustion engine, and radiator, of a suction pipe interposed between and connecting the radiator and intake of the engine and adapted to conduct moisture from the radiator to said intake, a valve controlling such suction pipe, means for short-circuiting the ignition current of said engine, and manually controlled means for simultaneously operating said valve and short circuiting means. 35

2. The combination with an internal combustion engine, and radiator, of a suction pipe interposed between and connecting the radiator and intake of the engine and adapted to conduct moisture from the radiator to said intake, a manually operable valve in 40 said suction pipe, and an ignition current short-circuiting device operable simultaneously with the opening of said valve. 45

In testimony whereof I affix my signature in presence of two witnesses.

GÖTTLIEB W. VOLZ.
